SOUNDING TOY

Russell T. Stewart and George Gardler, Atlantic
City, N. J.

Application April 19, 1934, Serial No. 721,369

8 Claims. (Cl. 46—46)

This invention relates to sounding toys, and it is an object of the invention to provide a device of this kind of a type adapted for use in connection with a percussion-cap strip together with a mechanism for coaction with such strip to produce an imitation of machine gun fire.

It is also an object of the invention to provide a device of this kind including a striker or hammer operated by a motor under control of a trigger, together with means to effect an intermittent feeding of a percussion-cap strip in accordance with the action of the striker or hammer.

The invention consists in the details of construction and in the combination and arrangement of the several parts of our improved sounding toys whereby certain important advantages are attained and the device rendered simpler, less expensive and otherwise more convenient and advantageous for use, as will be hereinafter more fully set forth.

The novel features of our invention will herein-after be definitely claimed.

In order that our invention may be the better understood, we will now proceed to describe the same with reference to the accompanying drawing, wherein:

Figure 1 is a view partly in front elevation and partly in section illustrating a sounding toy constructed in accordance with an embodiment of our invention;

Figure 2 is a fragmentary sectional view taken substantially on the line 2—2 of Figure 1 looking in the direction of the arrows;

Figure 3 is a detailed sectional view taken substantially on the line 3—3 of Figure 1 looking in the direction of the arrows;

Figure 4 is a detailed sectional view taken substantially on the line 4—4 of Figure 1 looking in the direction of the arrows;

Figure 5 is an enlarged fragmentary detail of the spring for throwing the hammer.

As disclosed in the accompanying drawing, 1 denotes a body member or stock which is preferably formed in simulation of a machine gun and suitably held by said body or stock at a predetermined point intermediate its ends and preferably depending therefrom is a cylindrical casing C. This casing C is of desired dimensions and has 50 its flat face disposed in a direction transversely of the body or stock 1. Suitably mounted within the casing C is a receptacle 2, a side face of which being preferably open and leading from said receptacle 2 is an elongated guideway 3 over which 55 is adapted to travel a percussion-cap strip 4.

This strip 4 is initially in the form of a roll and is placed around a centering pin 5 extending from the closed side 6 of the receptacle 2 or magazine as it may be termed.

The peripheral wall of the casing C adjacent 60 to the receptacle 2 is open, as at 7, as is also the adjacent portion 8 of the removable closure plate 9 which is disposed over a side face of the casing C. The outer portion of the guideway 3 carries an anvil 10 over which the strip 4 traverses for striking engagement by a hammer or striker 11. This hammer or striker 11 is carried by an arm 12 supported by a rod or shaft 14 for rocking movement. The arm 12 has a hub 15 which is freely engaged on the shaft or rod 14 65 and extending from said hub 15 is a rocker arm 16 which is normally in the path of travel of a double acting cam 17. This cam 17 rotates with the shaft 18 which is in driven connection, as at 19, with a power driven gear wheel 20. This 70 wheel 20 preferably is driven by a coil spring 21 adapted to be wound in a conventional manner. As the cam 17 contacts with the rock arm 16 the 75 striker or hammer 11 is retracted with respect to the anvil 10 but as the cam passes from the rock 80 arm 16 the hammer or striker 11 is forcibly brought into contact with the strip 4 upon the anvil 10 by the action of a spring 22. As herein disclosed, one end portion of the spring 22 is secured to and coiled around the hub 15 while the 85 opposite end portion of this spring is fixedly held, as at 23, in any desired manner. The hub 15 also carries a tail extension or second rock arm 24 with which is pivotally engaged, as at 25, a 90 blade 26.

This blade 26 has a toothed free end portion 27 which engages the strip 4 to feed the same forwardly a required distance with respect to the anvil 10 when the striker or hammer 11 is retracted under the action of the cam 17. The 95 blade 26 is constantly urged toward the guideway 3 or more particularly the strip 4 thereon by a spring 28 fixed to the tail-piece or rock arm 24 and bearing upon the blade 26. A second blade 30 positioned between the blade 26 and the guideway 3 has a toothed end portion 31 also contacting with the strip 4 and this blade 30 serves as a holding dog or pawl to prevent retrograde or return travel of the strip 4. This blade 30 has one end portion fixed to a shaft 32 rotatably 100 supported within the casing C and coacting with the shaft 32 in a well known manner is a spring 33 for constantly urging the toothed end portion 31 of the blade 30 into engagement with the 105 strip 4.

The shaft 32 carries a crank 34 whereby when desired the blade 30 can be swung away from the guideway 3 into an inoperative position and as this blade 30 is moved into such position it contacts with the blade 26 and also swings this blade into a raised or inoperative position. This means is provided to facilitate the initial placing of the strip 4.

In driven connection through the gears 35 with the gear 20 is a speed regulating fan including a disk 36. Normally in frictional contact with this disk 36 is a braking plate or member 37 carried by an endwise movable rod 38.

An expansible spring 39 operates to normally urge the braking plate or member 37 into contact with the disk 36 but upon proper pull being imposed upon the member or rod 38 the braking action on the disk 36 will be released and during which time of release the gear 20 will operate to effect the desired rocking or oscillation of the arm 12 resulting in successive explosions as a result of the hammer or striker 11 coming into forcible contact with the fulminates carried by the strip 4. When it is desired to "cease firing" it is only necessary that pull or strain on the member or rod 38 be released whereupon the spring 39 will automatically return the plate or member 37 into desired braking contact with the disk 36.

The member or rod 38 may be pulled in any desired manner but it is preferably to be attached to a trigger-like member suitably placed upon the stock 1.

From the foregoing description it is thought to be obvious that a sounding toy constructed in accordance with our invention is particularly well adapted for use by reason of the convenience and facility with which it may be assembled and operated, and it will also be obvious that our invention is susceptible of some change and modification without departing from the principles and spirit thereof and for this reason we do not wish to be understood as limiting ourselves to the precise arrangement and formation of the several parts herein shown in carrying out our invention in practice except as herein-after claimed.

We claim:—

1. A sounding toy comprising an anvil, an arm supported for swinging movement, a hammer carried by the arm for coaction with the anvil, means for guiding a percussion-cap strip to and over the anvil, means for intermittently rocking the arm in a direction to move the hammer away from the anvil, means for forcibly throwing the hammer toward the anvil after the hammer has been moved away from the anvil, and means operated by the arm when moving away from the anvil to feed the strip toward the anvil.

2. A sounding toy comprising an anvil, an arm supported for swinging movement, a hammer carried by the arm for coaction with the anvil, means for guiding a percussion-cap strip to and over the anvil, means for intermittently rocking the arm in a direction to move the hammer away from the anvil, means for forcibly throwing the hammer toward the anvil after the hammer has been moved away from the anvil, means operated by the arm when moving away from the anvil to feed the strip toward the anvil, and additional means for engagement with the strip to hold the same against return movement.

3. A sounding toy comprising an anvil, an arm supported for swinging movement, a hammer carried by the arm for coaction with the anvil, means for guiding a percussion-cap strip to and

over the anvil, a rock arm movable with the first named arm, said rock arm travelling in a general direction toward the anvil when the first named arm is moving in a direction therefrom, a blade pivotally engaged with the rock arm and coacting with the guiding means for the strip for moving the strip toward the anvil when the rock arm moves in a direction toward the anvil.

4. A sounding toy comprising an anvil, an arm supported for swinging movement, a hammer carried by the arm for coaction with the anvil, means for guiding a percussion-cap strip to and over the anvil, a rock arm movable with the first named arm, said rock arm travelling in a general direction toward the anvil when the first named arm is moving in a direction therefrom, a blade pivotally engaged with the rock arm and coacting with the guiding means for the strip for moving the strip toward the anvil when the rock arm moves in a direction toward the anvil, a second pivotally mounted blade interposed between the first named blade and the guiding means for coaction with the strip to hold the same against return movement.

5. A sounding toy comprising an anvil, an arm supported for swinging movement, a hammer carried by the arm for coaction with the anvil, means for guiding a percussion-cap strip to and over the anvil, a rock arm movable with the first named arm, said rock arm travelling in a general direction toward the anvil when the first named arm is moving in a direction therefrom, a blade pivotally engaged with the rock arm and coacting with the guiding means for the strip for moving the strip toward the anvil when the rock arm moves in a direction toward the anvil, a second pivotally mounted blade interposed between the first named blade and the guiding means for coaction with the strip to hold the same against return movement, and means for swinging the second named blade away from the guiding means.

6. A sounding toy comprising an anvil, an arm supported for swinging movement, a hammer carried by the arm for coaction with the anvil, means for guiding a percussion-cap strip to and over the anvil, a rock arm movable with the first named arm, said rock arm travelling in a general direction toward the anvil when the first named arm is moving in a direction therefrom, a blade pivotally engaged with the rock arm and coacting with the guiding means for the strip for moving the strip toward the anvil when the rock arm moves in a direction toward the anvil, a second pivotally mounted blade interposed between the first named blade and the guiding means for coaction with the strip to hold the same against return movement, and means for swinging the second named blade away from the guiding means, said second blade being of a length to contact with and move the first blade in a direction away from the guiding means.

7. A sounding toy comprising an anvil, an arm pivotally mounted therein for swinging movement, a hammer carried by the arm for coaction with the anvil, a rock arm carried by the pivoted end portion of the first named arm, a cam rotatably supported adjacent to the rock arm for intermittently imparting movement to said rock arm as the cam rotates for moving the first named arm and hammer away from the anvil, means for forcibly throwing the first named arm and hammer toward the anvil when the cam passes beyond the rock arm, and means for rotating the cam.

8. A sounding toy comprising an anvil, an arm pivotally mounted therein for swinging movement, a hammer carried by the arm for coaction with the anvil, a rock arm carried by the pivoted end portion of the first named arm, a cam rotatably supported adjacent to the rock arm for intermittently imparting movement to said rock arm as the cam rotates for moving the first

named arm and hammer away from the anvil, means for forcibly throwing the first named arm and hammer toward the anvil when the cam passes beyond the rock arm, means for rotating the cam, and means for braking said last named means. 80
